UNITED STATES PATENT OFFICE.

JOHN W. BARLOW, OF QUINCY, ILLINOIS.

SHOVELING-BOARD FOR BOX-WAGONS.

SPECIFICATION forming part of Letters Patent No. 601,010, dated March 22, 1898.

Application filed November 9, 1897. Serial No. 657,945. (No model.)

To all whom it may concern:

Be it known that I, JOHN W. BARLOW, a citizen of the United States, residing at Quincy, in the county of Adams and State of Illinois, have invented certain new and useful Improvements in End or Shoveling Boards for Box-Wagons; and I do hereby declare the following to be a full, clear, and exact description of the same, reference being had to the accompanying drawings, forming a part of this specification, and to the letters of reference marked thereon.

This invention has for its object to provide an improved mechanism for supporting and holding the end-board or shovel-board of a box-wagon in its several different positions of adjustment; and the invention consists in certain novel details of construction and combinations and arrangements of parts, all as will be now described, and the particular features of novelty pointed out in the appended claim.

Referring now to the accompanying drawings, Figure 1 is a perspective view of the rear end of a box-wagon body, showing the end-board thrown over the top of the body. Fig. 2 is a perspective view looking toward the rear end of the body, showing the end-board in position for closing the end of the body or constituting, in effect, an end-gate. Fig. 3 is a perspective view corresponding to Fig. 1 with the end-board in position for unloading or dumping, and Fig. 4 is a detail perspective view illustrating the construction of one of the hangers.

Like letters of reference in the several figures indicate the same parts.

I have shown my invention for convenience in connection with an ordinary form of box-wagon body having supplemental side-boards, the body proper of the wagon being indicated by the letter A and the supplemental side-boards being lettered B. This body is open at the rear end, as is ordinarily the case, and an end or shovel board is provided for either closing the end of the body or constituting an elongation or projection of the bottom thereof to facilitate unloading or dumping. This end-board is lettered C in the accompanying drawings, and it is preferably provided with tapering side pieces c to prevent the escape of material from the wagon-body later-

ally and to afford a convenient means for positioning and holding the end-board, as will presently appear. For supporting the end 55 of the board next the wagon-body the latter is provided with rearwardly-projecting hooks d, which take into or over a cross-piece c' on the end-board and afford a support therefor either when the board is in its horizontal position or when it is in its vertical position, as indicated, respectively, in Figs. 3 and 2.

On each of the side-boards A, near the rear end, I mount hangers E, Fig. 4, which hangers are provided with downwardly-extending 65 arms or points e on the inner sides of the side-boards A and with downwardly-extending projections e' on the outer sides. This construction will permit of the adjustment of such hangers to any ordinary wagon-body, 70 and longitudinal movement of the hangers may be prevented by inserting one of the arms e within the usual end-gate space or between the end-gate cleats f.

The arms e' of each of the hangers are provided with a series of holes adapted for the reception of bolts G, which bolts G constitute the support and connection for side links H, having their opposite ends pivotally connected to the sides of the end-board at an intermediate point. The connection between each of the links H and the end-board is preferably formed by an adjustable yoke K, having one of its arms made in the form of a bolt k, passing down through the end-board 80 and having a nut applied thereto for preventing its withdrawal. The opposite arm of the yoke K is provided with a series of holes or slots for the passage of a screw k', whereby it may be rigidly attached in its adjusted position to the side pieces of the end-board. The links H are provided with eyes at one end for the passage of the yokes K, and the opposite ends are provided with long slots for the bolts G, whereby the links are free to slide 85 longitudinally and to pivot upon said bolts. The relative positions of the yokes K and hangers E are such that when the end-board is turned up into vertical position, as illustrated in Fig. 2, the yoke will pass around the bolts G, and the links H will consequently be turned up into vertical or substantially vertical position. In order now to hold the end-gate in this position, I provide near the ex-

tremity of said end-gate fixed hooks or catches L, beneath which the ends of the links may be sprung, as illustrated in said Fig. 2.

The connection between the body and end-board, it will be observed, is such that the end-board is never free from its attachment. Consequently it cannot become lost or separated from the wagon-body, and at the same time it may be fastened in vertical position to constitute an end-gate of the wagon or in horizontal position, as in Fig. 3, when the links constitute diagonal braces for supporting it, or it may be turned up out of the way, as illustrated in Fig. 1, or swung down under the wagon-body by simply lifting it out of the hooks d and allowing it to swing down into position.

By forming the connection between the links H and the body adjustable the device may be adjusted to accommodate itself to wagon-bodies of different height, and, in fact, by means of the two adjustments at opposite ends of the link the device may be adjusted so as to cause the hangers to occupy any de-

sired angle, as well as to adapt themselves to different wagon-bodies, as just specified.

Having thus fully described my invention, what I claim as new, and desire to secure by Letters Patent, is—

The combination with the wagon-body A, 30 shoveling-board C and hooks d for detachably pivoting the edge of the board and body together, of the hangers E fitting over the edge of the side-boards of the body and having the series of holes, the bolts G adapted to 35 be secured in said holes, the adjustable yokes K secured to the edges of the board C, the links H having eyes engaging the yokes K and long slots at the opposite end through which the bolts G pass and hooks L on the 40 outer portion of the board for confining the links and holding the board in vertical position; substantially as described.

JOHN W. BARLOW.
